UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A BASQUE.

SPECIFICATION forming part of Design No. 18,389, dated June 19, 1888.

Application filed May 18, 1888. Serial No. 274,314. Term of patent 3½ years.

To all whom it may concern:

Be it known that I, HENRIETTA F. DUKE, of the city, county, and State of New York, have invented and produced a new and original Design for a Pattern of a Lady's Basque; and I do hereby declare that the engraved prints accompanying this specification convey to any one accustomed to using paper patterns a clear understanding of how a garment made up by the pattern will appear.

The design shows close-fitting fronts opening in curves from the neck over a full vest that exhibits a smocking extending nearly to the bust at the top and to the waist-line at the

bottom, and falling with a pointed effect between the flaring points of the short curved sides, a close-fitting postillion back that exhibits an underfolded fullness below its center seam, coat-sleeves, and a standing collar.

What I claim as my invention, and desire to secure by Letters Patent, is—

The design for a lady's basque, as shown in the engraved prints accompanying this specification.

HENRIETTA F. DUKE.
